(57) **CLAIM**

The ornamental design for a mobile terminal with an animated graphical user interface, as shown and described.

DESCRIPTION

FIG. 1 is a front view of a first image of a mobile terminal with an animated graphical user interface;

FIG. 2 is a front view of a second image thereof; and,
 FIG. 3 is a front view of a third image thereof.

The appearance of the image transitions sequentially between the images shown in FIGS. 1-3. The process or period in which an image transitions to another forms no part of the claimed design.

The broken line showing of the text in FIGS. 1 and 3 forms no part of the claimed design.
